United States Patent Office

Des. 178,416
Patented July 31, 1956

178,416

DESK LAMP

Fred Mugnai, Chicago, Ill., assignor to Art Specialty Co.,
Chicago, Ill., a corporation of Illinois

Application April 26, 1955, Serial No. 35,680

Term of patent 3½ years

(Cl. D48—20)

Fig. 1 is a side elevational view of a desk lamp showing my new design;

Fig. 2 is a front elevational view thereof;

Fig. 3 is a fragmentary elevational view looking upward into the face of the reflector thereof; and

Fig. 4 is a top plan thereof.

The dotted lines shown in Figs. 1 and 2 are for illustrative purposes only.

I claim:

The ornamental design for a desk lamp, as shown and described.
